UNITED STATES PATENT OFFICE.

LE ROY WILLOUR, OF ASHLAND, OHIO.

QUICK-ACTION JACK.

Specification of Letters Patent. Patented Mar. 14, 1916.

Application filed April 14, 1915. Serial No. 21,326.

1,175,211.

To all whom it may concern:

Be it known that I, Le Roy Willour, a citizen of the United States, residing at Ashland, in the county of Ashland and State of Ohio, have invented certain new and useful Improvements in Quick-Action Jacks, of which the following is a specification. My invention relates to improvements in lifting jacks, of the general type having a lift-bar operated by pawl and ratchet means.

An important object of the invention is to provide a jack of the above mentioned character, so constructed that the lift-bar will be advanced a step upwardly when the operating lever is swung downwardly and a step downwardly when the operating lever is swung upwardly, but the extent of upward movement of the lift-bar is substantially greater upon the down stroke of the lever, whereby the force necessary to swing the lever upwardly in advancing the lift-bar is substantially less than that required to move it downwardly, thus rendering the jack more convenient to operate.

A further object of the invention is to provide means for reversing the operation of the pawls so that they will lower the lift-bar as well as raise it.

A further object of the invention is to provide a jack of the above mentioned character, embodying a toothed lift-bar advanced by a pair of pawls, both of which are in engagement with the teeth of the lift-bar to support the load thereon when the operating lever is at rest.

A further object of the invention is to improve the construction of the pawl or pawls, and the spring means associated therewith.

A further object of the invention is to provide a support member or bar carried by the lift-bar and carrying an adjustable nose or rest.

A further object of the invention is to improve in general the construction of jacks of this type, with a view of rendering them more expeditious and reliable in operation.

A further object of the invention is to provide a jack of the above mentioned character, which is simple in construction, inexpensive to manufacture, strong and durable.

Other objects and advantages of the invention will be apparent during the course of the following description.

In the accompanying drawings forming a part of this specification and in which like numerals are employed to designate like parts throughout the same, Figure 1 is a side elevation of a lifting jack embodying my invention, Fig. 2 is a central vertical longitudinal sectional view through the same, parts being shown in elevation, Fig. 3 is a horizontal sectional view taken on line 3—3 of Fig. 1, Fig. 4 is a fragmentary side elevation of the upper portion of the jack, with the side plate removed for showing the control lever in the inactive position, Fig. 5 is a similar view with the control lever in the active position, Fig. 6 is a view similar to Fig. 2, with parts broken away, and the operating lever in the upper position, and, Fig. 7 is a perspective view of the side plate, Fig. 8 is a horizontal sectional view taken on line 8—8 of Fig. 4, and, Fig. 9 is a similar view taken on line 9—9 of Fig. 4.

In the drawings, wherein for the purpose of illustration is shown a preferred embodiment of my invention, the numeral 10 designates a preferably tubular standard, provided at its lower end with a foot or base 11, as shown. Formed upon the top or upper end of this standard is a housing 12, one side of which is closed and the opposite side open and normally covered by a removable side plate 13, held in place by a bolt 14, and trunnion 15, passing through apertures therein. The tubular standard 10 has its upper portion 16 projecting into the housing 12 and the bolt 14 and trunnion 15 are carried by such upper portion.

Mounted to reciprocate within the tubular standard 10 or having slidable engagement therewith is a lift-bar 17, provided upon one longitudinal edge with teeth or ratchet teeth 18, facing downwardly, as shown.

Arranged upon the side of the lift-bar 17 adjacent the teeth 18 is a pair of operating pawls 19 and 20, engaging the teeth, and arranged within the housing 12, as shown. The numeral 21 designates an operating lever or operating lever socket, having a head 22, extending into the housing 12 and operating in an opening 23 therein. This head turns upon a transverse pin or pivot element 24, which is spaced for substantial distances from the inner end and top of the head 22, as shown. The pawl 20 is substantially longer than the pawl 19 and these pawls have their pivot ends forked.

providing longitudinal slots 25, such forked ends being apertured for receiving pins or pivot elements 26 and 27, carried by the head 22. The pivot 27 of the pawl 19 is arranged inwardly and to one side of the pivot 24 and below it for a substantial distance, when the lever 21 is elevated, and above it for a substantial distance when lowered. The pivot 26 of the pawl 20 is arranged above and in substantially vertical alinement with the pivot 24 when the lever 21 is elevated and above and slightly outwardly of it when the lever is lowered. In other words, the pivot 27 of pawl 19 moves in a vertical arc while the pivot 26 of the pawl 20 moves in a horizontal arc, whereby pawl 19 is made to travel a substantially greater vertical distance than pawl 20. The operating lever 21 is provided with a depending stop lug 21' adapted to engage with a portion of the housing 12 and positively limit the downward movement of the lever while the upward movement thereof is limited by engagement of 25 the top of the lever 21 with the housing 12.

The numeral 28 designates a spring, having portions wound or coiled about the pins or pivots 26, 27, and arranged within the slots 25 of the pawls. The ends 29 of the 30 spring extend upwardly through the openings 25 and engage with the outer sides of the pawls 19 and 20.

The pawls 20 and 19 carry laterally extending pins 30 and 31 respectively, the pin 31 being longer than the pin 30 and projecting through the opening 32 in the plate 13, as shown. The numeral 33 designates a control lever, which is approximately hammer-shaped and provided at its upper end 40 with a laterally extending head 34 and near and beneath this head with a recess forming a cam face 35, adapted to engage respectively with the pins 30 and 31. At its lower end the control lever 33 is provided with an 45 aperture for pivotally receiving a lug or trunnion 36, carried by the open side of the housing 12, as shown. A spring 37 is coiled about a trunnion 36', with one end extending through an apertured lug 38 carried by 50 the lever 33 and its opposite end engaging a rib 39, carried by the housing 12. Pivotally mounted upon a trunnion 39' carried by the housing 12, is a latch 40, having a cam head 40', adapted to engage and disengage an 55 extension 41', formed upon the lower end of the lever 33, and depending therebelow, as shown. The function of this latch is to hold the control lever 33 in the inactive position, as shown in Fig. 4, whereby the pawls will 60 operate to raise the lift-bar, and when the latch is swung downwardly the control lever will be released and its spring will move it forwardly, whereby the same will engage with the pins carried by the pawls and the 65 pawls will lower the lift-bar upon the swing-

ing movement of the operating lever, as will be more fully explained.

The numeral 42 designates a lift-head, provided with a depending socket 43, detachably receiving the upper end of the lift-bar 17. Depending from this lift-head 42 and preferably formed integral therewith is a support-bar 43', embodying spaced sides 44 connected at their lower ends by a transverse web 45. These spaced sides are provided upon their inner surfaces with longitudinally extending ribs 46, provided in their lower portions with openings or notches 47 forming teeth 48. These teeth are provided upon their inner sides with preferably curved recesses 49, also formed upon the upper portions of the ribs above the teeth, for a purpose to be described.

The numeral 50 designates a vertically adjustable support-bracket or rest provided upon its inner side with a longitudinal rib 51, adapted to project into a longitudinal opening 52, occurring between the spaced ribs 46. At the upper end of the rib 51 is a T-shaped head 53, having its shank 54 adapted to pass through the opening 52 and its transverse head 55 adapted to be arranged inwardly of the ribs 46 and having curved faces to engage with the recesses 49 and thus constitute a pivot upon which the support bracket 50 may swing whereby a transverse tooth or teeth 56 carried by its lower end may be moved into and out of the openings or notches 47. It is thus apparent that the support bracket 50 is securely attached to the support-bar 43 and may be conveniently longitudinally adjusted thereon.

The operation of the jack is as follows: When it is desired to move the lift-bar 17 upwardly the latch 40 is swung upwardly 105 whereby the control lever 33 is held in the inactive position, out of engagement with the pins 30 and 31. When the lever 21 is swung upwardly, the upper pawl 20 engages with one of the ratchet teeth 18 raising the lift-bar a step while the lower pawl trips over the next lower tooth and engages therebeneath, and upon the downward movement of the operating lever the lower pawl elevates the lift-bar a step while the upper pawl trips over the next upper tooth, such 110 operation continuing throughout the upward movement of the lift-bar. It is thus apparent that the lift-bar is advanced a step upon the upward movement of the lever 21, as 115 well as the downward movement thereof. Particular attention is called to the fact that the lift-bar is advanced for a substantially greater distance upon the down stroke of the operating lever than upon the up stroke 120 thereof, that is about twice as great a distance. Of course these pawls are capable of moving the lift-bar longitudinally upon the upward and downward movement of the lever, by virtue of the fact that they are 125 130

pivoted to the operating lever upon opposite sides of its swinging pin 24, but the upper pawl 20 moves vertically only about half the distance of the vertical movement 5 of the lower pawl, and this is caused by the peculiar location of the pivots 26, 27, of these pawls with relation to the pivot 24, as hereinbefore described. This is an important feature of the invention, as by causing 10 the pawl-means to elevate the lift-bar 17 only half the distance, upon the up stroke of the lever 21, as upon the down stroke, the lever moving through the same distance upon the up and down strokes, only half the force 15 is necessary to raise the load upon the up stroke of the lever, it being well known that it is more convenient to exert considerable force upon the down stroke of the lever than upon its up stroke.

20 When it is desired to move the lift-bar downwardly, the latch 40 is moved downwardly to release the control lever 33 and the spring 37 moves the lever 33 forwardly whereby the end of the head 34 and the 25 cam 35 will engage the pins 30 and 31 respectively. The spring 37 is stiffer than the ends 29 of the spring 28, and will therefore automatically move each pawl from engagement with the teeth 18 of the lift-bar when 30 the load is taken off of the pawl. When the control lever 33 is in the active position and the lever 21 is swung to the extreme lower position with the stop lug 21' engaging the lower portion of the housing 12, the load 35 will be taken off of the upper pawl and the spring 37 will at once swing the control lever 33 forwardly so that its head 34 by engaging with pin 30 will move the outer pawl out of engagement with the teeth of 40 the lift-bar. Upon the upper stroke of the lever the upper end of the pawl 20 does not engage with the adjacent tooth but with the next upper tooth, thus allowing the lift-bar to descend and follow the downward 45 movement of the lower pawl 19, until the upper pawl engages with the next upper tooth. During this upward movement of the lever 21 the pin 31 slides upon cam 35, compressing the spring 37 as pawl 19 has the 50 load, but when the load is transferred to pawl 20, lever 33 moves outwardly, and carries pawl 20 out of engagement with the tooth, retaining the same in such disengaged 55 position for the down stroke of the outer pawl, but at the end of the down stroke the pin 31 again disengages the cam 35, whereby the inner pawl engages with the next upper tooth while the end of the head 34 approximately simultaneously engages with the pin 60 30 to cause the outer pawl to disengage with the teeth for the up stroke of the lever, as hereinabove described.

It is to be understood that the form of my invention herewith shown and described 65 is to be taken as a preferred example of the

same, and that various changes in the shape, size, and arrangement of parts may be resorted to without departing from the spirit of the invention or the scope of the subjoined claims.

Having thus described the invention, I claim:

1. In a lifting jack of the character described, a standard, a lift-bar slidably engaging therewith and provided with a longitudinal set of teeth, an operating lever pivotally connected with the standard near the teeth, a pair of pawls pivotally connected with the operating lever to engage with the teeth and provided near their pivots with 75 openings, and a spring having portions bent about the pivots of the pawls with its end portions extending outwardly through and beyond the openings of the pawls and engaging with the pawls to force them into 80 engagement with the teeth.

2. In a lifting jack of the character described, a standard, a lift-bar slidably engaging therewith and provided with a longitudinal set of teeth, an operating lever pivotally connected with the standard near the teeth, a pair of pawls having their free ends arranged to engage with the teeth and their opposite ends forked and apertured, pivot elements carried by the operating lever and 90 passing through the apertures of the pawls, and a spring including coiled portions surrounding the pivot elements within the forked ends of the pawls and having outwardly extending arms engaging with the 95 pawls to force them into engagement with the teeth.

3. In a lifting jack of the character described, a standard, a lift-bar slidably engaging therewith and provided with a longitudinal set of teeth, an operating lever pivotally connected with the standard near the teeth, a pawl arranged to engage with the teeth and having one end forked and apertured, a pivot element carried by the operating lever and extending through the aperture of the forked end of the pawl, a spring coiled about the pivot element within the forked end of the pawl and extending outwardly therebeyond for engagement with 115 the pawl, and a co-acting pawl arranged near the first named pawl to engage with the teeth.

4. In a jack of the character described, a standard, a lift-bar slidably engaging therewith, means to effect the longitudinal movement of the lift-bar, a support-bar connected with the lift-bar to move therewith and provided with spaced teeth extending longitudinally of the lift-bar, and a rest having 120 longitudinally adjustable engagement with the support-bar near the upper end of the rest and provided near its lower end with a tooth for detachable engagement with the teeth of the support-bar.

5. In a jack of the character described, a standard, a lift-bar having slideable engagement therewith, means to effect the longitudinal movement of the lift-bar, a support-bar connected with the lift-bar to move therewith and provided with longitudinal ribs and spaced teeth arranged beneath the ribs, and a rest provided near its upper end with a headed member to engage upon the 10 inner sides of the ribs and near its lower end with a tooth for detachable engagement with the spaced teeth of the support-bar.
6. In a jack of the character described, a standard, a lift-bar having slideable engagement therewith, means to effect the longitudinal movement of the lift-bar, a support-bar connected with the lift-bar to move 15

therewith, and including spaced sides provided with interiorly arranged longitudinal ribs and spaced teeth disposed beneath the 20 ribs, a support-bracket to be longitudinally adjustably mounted upon the support-bar, a substantially T-shaped member secured to the upper end of the support-bracket to engage with the ribs, and a laterally extending tooth carried by the lower end of the support-bracket to engage with the teeth 25 of the support-bar.

In testimony whereof I affix my signature in presence of two witnesses.

LE ROY WILLOUR.
